UNITED STATES PATENT OFFICE

HERMAN C. REICHARDT, OF EVANSTON, ILLINOIS, ASSIGNOR, BY DIRECT AND MESNE ASSIGNMENTS, TO STAR-BRITE CORPORATION, OF CHICAGO, ILLINOIS, A CORPORATION OF ILLINOIS

DESIGN FOR A VEHICLE REAR LIGHT CASING

Application filed December 31, 1931. Serial No. 42,329. Term of patent 7 years.

To all whom it may concern:

Be it known that I, HERMAN C. REICHARDT, a citizen of the United States, residing in the city of Evanston, in the county of Cook and State of Illinois, have invented a new, original, and ornamental Design for Vehicle Rear-Light Casing, of which the following is the specification, reference being had to the accompanying drawing, forming part thereof.

Figure 1 is a side elevation of the casing showing an opening in the side face of the casing and shows the solid wall on the other side of the casing through said opening.

Figure 2 is a front elevation of the casing and shows an opening in the front face of the casing, and the back wall through the opening in the front face.

Figure 3 is a rear elevation of the casing.

Figure 4 is a bottom plan view of the casing.

Figure 5 is a cross-sectional view through the casing.

I claim:

The ornamental design for vehicle rear-light casing as shown.

HERMAN C. REICHARDT.
